ELECTRODE-SUPPORTING ROD FOR ELECTROLYTIC TANKS.

1,074,088.

Specification of Letters Patent. Patented Sept. 23, 1913.

Application filed April 9, 1913. Serial No. 759,891.

To all whom it may concern:

Be it known that I, PETER JENSEN, a citizen of the United States, and a resident of Perth Amboy, in the county of Middlesex 5 and State of New Jersey, have invented a new and Improved Electrode-Supporting Rod for Electrolytic Tanks, of which the following is a full, clear, and exact description.

- 10 The copper rods now employed in connection with electrolytic tanks for supporting the electrodes are round in cross-section, and consequently the surface quickly becomes coated with dirt and other foreign 15 matter, which greatly impairs the efficiency because of the poor contacts obtained between the suspended hooks of the electrodes and rods. Because of these poor contacts greater electric power is required to obtain 20 the best results. Heretofore it has been the practice in order to maintain the proper contacts to frequently clean and polish the copper supporting rods by emery paper, which is a great item of expense, both for 25 service and for the emery paper.

It is the object of the present invention to so construct the supporting rods for the electrodes that dirt cannot readily lodge thereon, and effective current conducting 30 contacts can be maintained between the suspending hooks of the electrodes and the rods without the necessity of using emery paper or the equivalent to keep the rods in proper condition, as is now necessary.

35 The supporting rods are preferably made of squared or angular stock and twisted so that the longitudinal edges of the stock will form spirals which are of such pitch that each hook of the electrode will be engaged with a plurality of the spiral edges. In other words, each hook has a multiple-point contact with the supporting rod, and because of the peculiar shape of the rod dirt or foreign matter does not accumulate 40 on the edges with which the suspending hooks or lugs of the electrode engage. The ends of the rod are longitudinally grooved to form V-shaped ridges which rest on the bus-bar of the tank; so that a multiple-point 45 contact is obtained between the copper supporting bars and the bus-bar.

With these objects in view, and others as will appear as the description proceeds, the invention comprises various novel features 50 of construction and arrangement of parts

which will be more fully described herein-after and set forth with particularity in the claims appended hereto.

In the accompanying drawings, which illustrate one embodiment of the invention, 60 and wherein similar reference characters are employed to designate corresponding parts throughout the several views, Figure 1 is a perspective view of an electrode supporting bar in position and suspending an 65 electrode; Fig. 2 is a fragmentary view of a supporting bar with an electrode engaged therewith; and Fig. 3 is a perspective view of the rod before the same is twisted.

Referring to the drawing, A designates 70 a copper supporting rod or conductor, B the copper plate or electrode, C the bus-bar supporting one end of the conductor, and D the insulating support for the other end of the conductor. The intermediate portion 75 1 of the electrode supporting rod or conductor is angular in cross-section in its original form, as shown in Fig. 3, and this portion of angular cross-section is twisted so that the straight edges 2, Fig. 3, will be 80 converted into helices, as shown in Fig. 1, the pitch of which may be such that the suspending hooks or lugs 3 of the electrode B will engage a plurality of spiral edges 2. Between the edges 2 are helical grooves 4, 85 which are out of contact with the suspending lugs 3. In other words, it is only the spiral edges or crests 2 that contact with the lugs. By reason of the shape of the electrode-engaging portion of the rod A, 90 dirt cannot accumulate on the rod to impair electrical engagement between the latter and the electrode suspending hooks, or, at least, dirt or foreign matter will not accumulate on the spiral edges which engage the said 95 hooks. Even if the electrodes are shifted longitudinally on their supporting rods, effective electrical contacts will be obtained because of the spiral edges 2 being always clean. Heretofore, if the electrodes were 100 shifted on their rods, the lugs would contact with dirt-covered portions, and as a result the electrical contact would be impaired.

The extremities 4 of the rod A have reversely-disposed longitudinally-grooved 105 faces 5 formed with V-shaped ridges 6, so that, when placed in position, the ridges at one end of the bar A will engage the bus-bar C and insure an effective electrical contact. By reversely arranging the ridges 110

6 at the opposite ends of the rod the latter
can be reversed.

From the foregoing description taken in
connection with the accompanying draw-
5 ings, the advantages of the method of op-
eration and of the device shown will be
readily understood by those skilled in the
art to which the invention appertains, and
while I have described the device which I
10 now consider to be the best embodiment
thereof, I desire to have it understood that
the device shown is merely illustrative, and
that such changes may be made when de-
sired as are within the scope of the append-
15 ed claims.

Having thus described my invention, I
claim as new and desire to secure by Let-
ters Patent:

1. An electrode suspending rod formed
20 from angular stock and twisted around its
longitudinal axis for producing a plurality
of helical edges for engaging the suspend-
ing hooks of an electrode.

2. An electrode supporting rod or con-

ductor having a plurality of helical elec- 25
trode-engaging edges.

3. An electrode supporting rod or con-
ductor having a plurality of helical elec-
trode-engaging edges and longitudinally-
extending ridges arranged in a common 30
plane at the extremities of the rod.

4. A supporting rod having a plurality
of sharp edges and grooves between the
edges, in combination with an electrode hav-
ing a plurality of hooks engaging the said 35
edges.

5. An electrode supporting rod having a
sharp edge extending helically thereof, and
an electrode having a plurality of hooks all
engaging said edge for electrically connect- 40
ing the electrode to the rod.

In testimony whereof I have signed my
name to this specification in the presence of
two subscribing witnesses.

PETER JENSEN.
